United States Patent Office

Des. 192,590
Patented Apr. 10, 1962

192,590

NAIL CLIPPER

Norbert Leopoldi, 4180 Marine Drive, Chicago, Ill.

Filed Oct. 20, 1961, Ser. No. 67,190

Term of patent 14 years

(Cl. D86—10)

I claim:

The ornamental design for a nail clipper, substantially as shown.
